UNITED STATES PATENT OFFICE

154,050

DESIGN FOR A CHILD'S ROCKING HORSE

William S. Mandina, Kansas City, Mo.

Application March 15, 1948, Serial No. 145,102

Term of patent 14 years

(Cl. D34—15)

To all whom it may concern:

Be it known that I, William S. Mandina, a citizen of the United States, residing at Kansas City, in the county of Jackson and State of Missouri, have invented a new, original, and ornamental Design for a Child's Rocking Horse, of which the following is a specification, reference being had to the accompanying drawing, forming a part thereof.

Figure 1 is a top plan view of the child's rocking horse, showing my new design.

Fig. 2 is a side elevational view thereof.

Fig. 3 is a front end view thereof; and

Fig. 4 is a view showing the rear end thereof.

I claim:

The ornamental design for a child's rocking horse, as shown.

WILLIAM S. MANDINA.
